ANTI-COLLISION STROBE LIGHT FOR AIRCRAFT

John L. Jiruska, Annapolis, Md., assignor to Jackson Products Corporation, Annapolis, Md., a corporation of Maryland

Filed Oct. 16, 1967, Ser. No. 9,011

Term of patent 14 years

(Cl. D48—24)

FIG. 1 is a perspective view of the anti-collision strobe light for aircraft embodying my design;

FIG. 2 is a top plan view thereof;

FIG. 3 is a side elevational thereof;

FIG. 4 is a bottom plan view thereof; and

FIG. 5 is a side elevation thereof similar to FIG. 3 but turned 90° clockwise.

I claim:

The ornamental design for an anti-collision strobe light for aircraft, as shown.
